BELT CONVEYER

John R. Madeira, Chicago, Ill., assignor to Goodman Manufacturing Company, Chicago, Ill., a corporation of Illinois

Application June 21, 1944, Serial No. 541,304

10 Claims. (Cl. 198—109)

This invention relates to improvements in belt conveyers, and more particularly to improvements in sectional belt conveyers of the troughed belt type adapted for use in mines underground.

The principal objects of my invention are to provide a new and improved sectional conveyor of the troughed belt type having a novel form of connection between the sections of the conveyor, permitting the conveyor to follow an uneven bottom and taking the loads from one end of the conveyor to the other on the spacing members carrying the idler rollers of the conveyor, and taking all of the weight and shearing stresses from the means for holding the sections of the conveyor in connected relation with respect to each other.

In carrying out my invention I provide a plurality of intermediate supporting standards between the head and tail ends of the conveyor and space these supporting standards apart and pivotally connect them together by spacing members, and construct these spacing members to take the end thrusting loads from one end of the conveyor to the other so as to relieve these loads from said supporting standards and the means for connecting said spacing members to said supporting standards, and also provide a rocking support for said spacing members on said supporting standards, so as to relieve the connecting means between said spacing members and standards from carrying the weight of the conveyor.

Other objects of my invention will appear from time to time as the following specification proceeds and with reference to the accompanying drawing wherein:

Figure 1 is a view in side elevation of an intermediate portion of a sectional troughed belt conveyor constructed in accordance with my invention;

Figure 2 is an enlarged view of one of the supporting standards, with parts thereof broken away in order to illustrate the connection between the spacing members and standards of the conveyor; and

Figure 3 is an enlarged fragmentary transverse sectional view taken through the conveyor and showing certain other details of the connection between the spacing members and standards not shown in Figures 1 and 2.

In the embodiment of my invention illustrated in the drawing, a plurality of transverse supporting standards 10, 10 are connected together by spacing members 11, 11, which form a support

means for the upper and lower runs of a conveyor belt 12.

Each supporting standard 10 includes a pair of laterally spaced parallel upright legs 13, 13 which are connected together at their lower ends by a transverse connecting member 14, herein shown as being a channel iron welded to the insides of said legs at its ends.

Each leg 11, as herein shown, is formed from a channel iron with the flanges thereof extending outwardly from the center of the conveyor and mounted on a bearing plate 15 adapted to rest on the ground. Each of said legs is also provided with a horizontal ledge 16 spaced upwardly from the bottom thereof and extending inwardly therefrom, on which is adapted to rest rocking bearing members 17, 17 secured to the bottoms of adjacent ends of the spacing members 11, 11.

The spacing members 11, 11 are herein shown as being channels having their flanges facing outwardly and forming support means for carrier brackets 18, 18 which have idlers 19, 20 journaled thereon in a well known manner, and arranged to form the conveyor belt 12 into a trough-shaped formation. Idler rollers 21, 21 for supporting the lower run of the belt are mounted on the lower sides of said spacing members on brackets 22, 22. Detachable covers 23, 23 bridge said spacing members and cover the lower run 30 of the belt to prevent material from spilling on the inside of the lower run of the belt.

The means for holding the spacing members 11, 11 to the standards 10, 10 includes a plate 27 mounted at each end of each spacing member, 35 between the flanges thereof and having a pivotal pin 26 projecting therefrom. Said pivotal pins are herein shown as being cap screws threaded in said plates and adapted to loosely extend through suitable apertures formed in the webs 40 of the channels forming the legs 13, 13, to hold said spacing members to said legs.

Pivotal movement of said spacing members with respect to said standards is limited by cap screws 30, 30 threaded in the plates 27, 27 above the pins 26, 26 and extending through longitudinally extending arcuate slots 31, 31 formed in the legs 13, 13.

It should here be noted that since the connection between the pins 26, 26 and 30, 30 on the spacing members 11, 11 and the legs 13, 13 is relatively loose, and since the entire weight of said spacing members is taken on the ledges 16, 16 that the weight of the conveyor is removed from said pins 26 and 30 and that said pins 26 and 30 take no shearing loads and serve only to

connect said spacing members to said supporting standards.

Referring now in particular to the means for transmitting the end thrusting loads through said spacing members from one end of the conveyer to the other, each plate 27 is herein shown as having an arcuate formed lug 33, projecting outwardly from its end, and herein shown as being formed integral therewith. Said arcuate formed lugs are adapted to abut each other and form a rolling contact surface between adjacent ends of said spacing members, and thus take all end thrusting loads off of the supporting standards 10, 10 and take all shearing loads from the pins 26 and 30 and cause the end thrusting loads from one end of the conveyer to the other to be taken through said spacing members.

The arcuate faces of the rocking bearing members 17, 17 and of the bearing lugs 33, 33 are struck from a common radius, the centers of which are the centers of the pins 26, 26. The spacing members 11, 11 supported on the ledges 16, 16 on said rocking members will thus rock about axes concentric with the centers of said pins. This will insure that the weight of said spacing members is taken on said ledges rather than said pins and will avoid placing any undue stresses on said pins which might be caused if the faces of said rocking members and bearing lugs were struck from different radii or from arcs eccentric of the centers of said pins.

It may be seen from the foregoing that a novel form of sectional belt conveyer has been provided which may readily conform to an uneven mine bottom and which is so arranged that the only load taken by the intermediate supporting standards is the dead weight of the conveyer, and the only loads taken by the connecting means connecting the spacing members to the supporting standards are the thrusting loads against the heads of the cap screws, which may be caused by twisting of the conveyer frame where the frame is misaligned.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, except as it may be limited in the appended claims.

I claim as my invention:

1. In a sectional belt conveyer structure, a series of spaced apart supporting standards, a plurality of pairs of longitudinally extending spacing members connecting said standards together, said standards each including a pair of connected parallel spaced supporting legs, transverse pivotal connections between said supporting legs and said spacing members, and means for taking the end thrust loads off said pivotal connections and transmitting said loads through said spacing members longitudinally of the conveyer including arcuately formed abutting surfaces on adjacent ends of said spacing members, forming rolling abutting joints between said spacing members, to permit said conveyer to conform to an irregular mine bottom.

2. In a sectional conveyer structure, a series of spaced apart supporting standards, a plurality of longitudinally extending spacing members connecting said standards together, said standards each including a pair of connected parallel

spaced supporting legs, transverse pivotal connections between said spacing members and adjacent ends of said supporting legs, and arcuately formed lugs on the ends of said spacing members, said lugs of adjacent spacing members being adapted to have abutting engagement with each other and the arcuate faces of said lugs being struck from centers coaxial with the axes of said pivotal connections, to form a rolling connection

therebetween, to permit said conveyer to conform to an irregular mine bottom and to transmit the end thrust loads through said spacing members longitudinally of the conveyer, to take said loads off of said pivotal connections and said supporting standards.

3. In a sectional conveyer structure, a series of spaced apart supporting standards, a plurality of longitudinally extending spacing members connecting said standards together, said standards each including a pair of connected parallel spaced supporting legs, transverse pivotal connections between said spacing members and adjacent ends of said supporting legs, arcuately formed lugs on the lower end portions of said spacing members struck from centers coaxial with the axes of said pivotal connections, and a supporting ledge on each of said supporting legs adapted to have said arcuately formed lugs rest thereon to take the weight of said conveyer off of said pivotal connections and to form a rocking support for said spacing members on said supporting standards.

4. In a sectional conveyer structure, a series of spaced apart supporting standards, a plurality of longitudinally extending spacing members connecting said standards together, said standards each including a pair of connected parallel spaced supporting legs, transverse pivotal connections between said spacing members and adjacent ends of said supporting legs, supporting ledges on said supporting legs, arcuately formed rocking lugs on the lower sides of said spacing members adapted to rest on said ledges to form rocking supports for said spacing members on said supporting standards, and arcuately formed lugs on the ends of said spacing members, said lugs on the ends and the lower sides of said spacing members being struck from a common radius, the center of which is coaxial with the axis of said associated pivotal connection, and said lugs of adjacent spacing members being adapted to have abutting engagement with each other to form a rolling connection therebetween and to transmit the end thrust loads of the conveyer through said spacing members.

5. In a sectional conveyer structure, a series of spaced apart supporting standards, a plurality of longitudinally extending spacing members connecting said standards together, said standards each including a pair of connected parallel spaced supporting legs, transverse pivotal pins connecting adjacent ends of said supporting legs with said spacing members, a pin and slot connection spaced from said pivotal pins, for limiting pivotal movement of said spacing members with respect to said standards, and arcuately formed lugs on the ends of said spacing members, said lugs of adjacent ends of said spacing members being adapted to have abutting engagement with each other, to form a rolling connection therebetween, to take the shearing loads from said pivotal pins and to transmit the end thrust loads of the conveyer through said spacing members.

6. In a sectional conveyer structure, a series of spaced apart supporting standards, a plurality of longitudinally extending spacing members con-

necting said standards together, said standards each including a pair of connected parallel spaced supporting legs, transverse pivotal pins connecting adjacent ends of said supporting legs with said spacing members, a pin and slot connection spaced from said pivotal pins for limiting pivotal movement of said spacing members with respect to said standards, a supporting ledge on each of said supporting legs, and an arcuately formed lug on the underside of each spacing member adapted to rest on said ledge and form a rocking support for its associated spacing member on said ledge to relieve the weight of said associated spacing member from said pivotal pin.

7. In a sectional conveyer structure, a series of spaced apart supporting standards, a plurality of longitudinally extending spacing members connecting said standards together, said standards each including a pair of connected parallel spaced supporting legs, transverse pivotal pins connecting adjacent ends of said supporting legs with said spacing members, a pin and slot connection spaced from said pivotal pins for limiting pivotal movement of said spacing members with respect to said standards, a supporting ledge on each of said supporting legs, and an arcuately formed lug on the underside of each spacing member adapted to rest on said ledge and form a rocking support for its associated spacing member on said ledge, and to relieve the weight of said associated spacing member from said pivotal pin, and arcuately formed lugs on the ends of said spacing members, said lugs of adjacent spacing members being adapted to have abutting engagement with each other to form a rolling connection therebetween and to transmit the end thrust loads of the conveyer through said spacing members longitudinally of the conveyer, said lugs on the ends of said spacing members and

5 said lugs on the bottoms thereof serving to take the end thrust loads transmitted by said spacing members and to take the weight of the conveyer from said pivotal pins, and said pivotal pins serving only to retain said spacing members on said standards.

8. In a structural unit for a sectional conveyer, a supporting standard for one end of said unit including an upright leg, a longitudinally extending spacing member pivotally connected to said supporting leg on a transverse axis, said spacing member having an arcuately formed abutting surface at its end coaxial with its pivotal connection, to provide rolling abutting engagement with a longitudinally extending spacing member of an adjoining conveyer unit.

9. In a structural unit for a sectional conveyer, a supporting standard for one end of said unit including a pair of connected spaced apart legs, 10 a pair of longitudinally extending spacing members each having an arcuately formed abutting surface at its end coaxial with its pivotal connection, to provide rolling abutting engagement with a longitudinally extending spacing member of 15 an adjoining conveyer unit.

10. In a structural unit for a sectional conveyer, a supporting standard for one end of said unit including a supporting ledge and an upright supporting leg, a longitudinally extending spacing member, transverse pivotal connections between said spacing member and said leg, arcuately formed rocking lugs on the lower end portion of said spacing member coaxial with said pivotal connections, having rolling engagement 20 with said supporting ledge and also providing a rolling abutting engagement at its end with a longitudinally extending spacing member of an adjoining conveyer unit.

JOHN R. MADEIRA.
